UNITED STATES PATENT OFFICE.

JESS J. MORRIS AND MARTIN EITEL, OF COLUMBUS, OHIO.

VALVE-GRINDING TOOL.

1,150,874.

Specification of Letters Patent. Patented Aug. 24, 1915.

Application filed January 26, 1914. Serial No. 814,309.

To all whom it may concern:

Be it known that we, JESS J. MORRIS and MARTIN EITEL, citizens of the United States, residing at Columbus, in the county of 5 Franklin and State of Ohio, have invented certain new and useful Improvements in Valve-Grinding Tools, of which the following is a specification.

Our invention relates to valve grinding tools and aims particularly to provide a type of tool in which a number may be used as a unit for simultaneously grinding a number or all of the valves of an internal combustion engine. We have provided a 15 tool which may be rigidly set in position upon the cylinders of an internal combustion engine, and by resorting to the use of a longitudinally extensible or adjustable connection between such elements, power may 20 be applied in any desired manner and all of the valves ground simultaneously.

A further object of our invention is to provide a structure wherein the valves may be ground by the repeated turning over of 25 the engine itself. To do this, we aim to provide a driving connection between the crank shaft of the engine and the tools, after they are operatively mounted in position above the valves. We have further provided a 30 yielding structure operable with the main shaft of the tool itself, which is rotated to turn the valve heads. This yielding connection permits the raising and lowering of the valve heads themselves, the same as 35 would be the case in their actual operation, but always presenting a new surface to the valve seats when the valves are again seated.

Other objects of our invention will become more apparent after a detailed description 40 of the accompanying drawings, in which similar characters of reference designate corresponding parts, and in which:

Figure 1 shows one form of internal combustion engine with our grinding tools 45 mounted in position to form a grinding unit, Fig. 2 is a longitudinal vertical section of one of the valve grinding tools, and, Fig. 3 is an elevation of the tool shown in Fig. 2 and taken at right angles to that of Fig. 2.

In the drawings, we have shown one form 50 of engine designated in its entirety by the numeral 1, which engine is also provided with a valve casing shown at 2. It is customary in all modern combustion engines, particularly those used in connection with mo-

tor vehicles, to provide a removable cap above each of the intake and exhaust valves, which caps may be removed to effect the grinding operation. Further, the heads of practically all of the valves of the puppet type, are provided with a slot accommodating the insertion of the small end of a screw driver. We have, therefore, designed our structure to accommodate this modern construction and the tools themselves are designated bodily as 3, Fig. 1 showing four of these tools in their applied position. Each tool is provided with two outwardly projecting stub shafts 4 and 5, as will be hereinafter described, these shafts serving to 70 apply and transmit the power for driving from any suitable source. Inasmuch as the distance between cylinders and between valves of various types of engines may vary, we have provided a longitudinally extensible 75 or adjustable connection, this connection taking the form of sleeves designated 6 and 7, the sleeve 6 being adapted to be securely mounted in position upon the stub shafts as mentioned, when the tools are applied to 80 the valves of one cylinder, while the sleeve 7 forms a driving connection between the tools of adjacent cylinders. It will be noted that the sleeves 6 and 7 are shown as being held in their rigid position by means of set 85 screws 8 and it will be further understood that the stub shafts 4 and 5 and the sleeves 6 and 7 are of relative lengths to permit of the use of driving connections between tools 90 for distances covering the range of distances between all cylinders and valves of modern engines. Further, the stub shaft 4 upon the tool used in connection with the first cylinder is also provided with a sleeve which may be either 6 or 7 and which sleeve is provided 95 with any type of driving connection, such as is shown by the pulley 9 and belt 10, it being understood that power may be transmitted from any suitable source and may also be conveniently connected to the crank shaft 100 of the engine itself, this forming a convenient arrangement, but not limiting the scope of our invention.

Each of the tools 3, as is more clearly shown in Figs. 2 and 3, comprises a main 105 body member 11 suitably shaped to form a journal for the rotatable shaft 12 removably carrying a valve engaging member 13 in a slot 14 in its lower end by means of the cotter 15. At its upper end, this shaft is 110

provided in any suitable manner with a bevel gear 16, which bevel gear is adapted to mesh with each of the bevel pinions 17 disposed on opposite sides of the tool and carried by the stub shafts 4 and 5. It will be noted that the stub shafts 4 and 5 are suitably journaled by the coöperation of the body member 11 with the cap structure 18, which cap structure also carries an upwardly extending housing 19 within which is incased a spring 20 adapted to bear upon the upper end of the shaft 12 and to thereby maintain the gear 16 in mesh with the pinions 17. Further, the tension of the spring 20 may be regulated by the vertical adjustment of the cap screw shown at 21, which cap screw may be removed, if desired, to permit the placing of oil upon the gears, and then replaced. The body member 11 and the cap member 18 are each provided with laterally projecting ears 22 and 23 respectively, which ears, together with the screws 24 serve as a means of uniting the two sections, as is clearly illustrated. The lower end of the body member 25 is also provided with an outwardly projecting shoulder 25 having its outer edge threaded and adapted to receive the collar 26. The shoulder 25 is also provided with a series of apertures 27, which may serve as a means of permitting the placement of the grinding preparation between the valve and its seat when the tool is mounted in its operative position. It must also be apparent that the collar 26, being threaded as is shown at 28, is adapted to be screwed into that portion of the cylinder above the valves themselves. It will be noted that we have made this collar portion detachable, for the reason that the removable caps normally carried above the valves of an ordinary engine, may at some time vary, although these caps are usually of a standard size. In the event that one is found that is not of a standard size, the collar 26 may be removed 45 and a supplemental collar used.

The operation of our device when used as a grinding unit, has been previously described and the operation of the tool itself is as follows: The body 11 is mounted in position with the valve engaging portion 13 in an operative position with the valve head. Turning of the stub shaft 4 will cause rotation of the main shaft 12 and also the stub shaft 5, whereby power is transmitted to the adjacent tool. If this power is taken by connecting the stub shaft 4 in some manner with the crank shaft of the engine and turning the engine over repeatedly, the spring 20 permits the elevation of the valve, the same as is done during the normal operation of the engine. It is understood that the elevation of the shaft 12 causes disengagement of the gear 16 with its pinions 17, but the spring will force these members to again 60 come into mesh as soon as the valve has

seated itself. Should it be desired to regulate the tension between the valve cap and its seat, the cap screw 21 may be adjusted to cause increased tension of the spring 20.

What we claim, is:

1. A valve grinding unit comprising a plurality of grinding tools rigidly set in position on an engine in operative relation to its valves, means for applying power directly to one of said tools, and a detachable driving connection between said tools ⁷⁵.

2. A valve grinding unit comprising a plurality of grinding tools rigidly set in position on an engine in operative relation to its valves, a stub shaft projecting from opposite sides of each tool and forming the means for transmitting power to said tools, means for applying power directly to one of said tools, and a sleeve connection between the stub shaft of adjacent tools and secured to said stub shaft in a manner to be longitudinally adjustable. ⁸⁰

3. A valve grinding unit comprising a plurality of grinding tools rigidly and individually set in position on an engine in operative relation to its valves, a structure for applying power to the first of said tools, and readily detachable driving connections between the succeeding tools. ⁹⁰

4. A valve grinding unit comprising a plurality of grinding tools each provided with a threaded base portion adapted to be screwed into an engine in operative relation to its valves, means for applying power directly to one of said tools, and coupling means between the remainder of said tools. ¹⁰⁰

5. A valve grinding unit comprising a plurality of grinding tools each individually set in position on an engine in operative relation to its valves, a rotatable shaft forming a part of each tool, a gear on each shaft, stub shafts for said tools, gears for said stub shafts, coupling means for each pair of tools connecting said stub shafts, and means for applying power directly to one of said tools. ¹⁰⁵

6. A valve grinder comprising a plurality of upstanding shafts, a valve engaging member carried by one end of each shaft, said shafts being mounted to permit their up and down movement when said members are in engagement with the engine valves, a bevel gear carried by each of said shafts, laterally projecting stub shafts between each pair of upstanding shafts, and complementary bevel pinions on said stub shafts arranged to mesh with said bevel gears on said upstanding shafts. ¹¹⁵

7. A valve grinder comprising a plurality of upstanding shafts, a valve engaging member carried by one end of each shaft, said shafts being mounted to permit up and down movement when said members are in engagement with the engine valves, means ¹²⁵ ¹³⁰ ¹³⁵

for normally forcing said shafts toward the engine valves, and driving connections between the various upstanding shafts.

8. A valve grinding tool comprising a body member adapted to be rigidly set in position on an engine in operative relation to one of its valves, a shaft rotatably journaled in said body, a bevel gear operatively mounted on said shaft, two laterally projecting stub shafts extending out on opposite sides of said body, and complementary bevel gears for said stub shafts meshing with said first named bevel gear.

9. A valve grinding tool comprising a body member adapted to be rigidly set in position on an engine in operative relation to one of its valves, a shaft rotatably jour-

naled in said body, a bevel gear carried by the upper end of said shaft, laterally extending stub shafts, bevel pinions carried by 20 said stub shafts and adapted to mesh with said bevel gear, a cap carried by said body, and a spring within said cap and adapted to bear upon the upper end of said first-named shaft thereby permitting its movement longitudinally with respect to said body.

In testimony whereof we affix our signatures in presence of two witnesses.
